INVENTOR.

E. B. Rich

United States Patent Office.

ELISHA B. RICH, OF SOUTH BOSTON, MASSACHUSETTS.

Letters Patent No. 97,813, dated December 14, 1869.

IMPROVEMENT IN SHIP-WINDLASSES.

The Schedule referred to in these Letters Patent and making part of the same.

To all persons to whom these presents shall come:

Be it known that I, ELISHA B. RICH, of South Boston, in the county of Suffolk, and State of Massachusetts, have invented a certain new and useful Improvement in Ships' Windlasses; and that the following is a full and exact description of the same, reference being had to the accompanying plate of drawings.

The present invention relates to windlasses for ships' uses, such as letting go and hauling in anchors or cables, and particularly to the pawl or device employed for arresting the turning of the windlass when the desired amount of cable has unwound, in letting go anchor, and to there hold it, as well as also in "hoisting anchor," to prevent the windlass from turning back, &c.

These pawls are subjected to sudden strains or shocks, among other causes, by the sudden bringing up of the anchor-cable in letting go anchor; when they are dropped into the windlass-ratchet to stop further paying out of cable; by the riding or surging of the ship when at anchor; and by the dragging of anchor, &c., by which sudden strains, oftentimes, their breakage or that of the windlass occurs, and other damages necessarily.

By this invention, the pawl is so constructed as to be susceptible of relieving or giving to any sudden strain or pressure on it, while at the same time, under ordinary pressure, it holds the windlass as fast as a pawl of common construction.

In the accompanying plate of drawings, my improvement in ships' windlasses is illustrated—

Figure 1 being a front elevation of the same.

Figure 2, a transverse vertical section, taken in the plane of the line *x x*, fig. 1.

Figure 3, a face view of the pawl by itself, on an enlarged scale from that by which it is shown in the preceding figures.

A, in the drawings, represents the windlass-drum or barrel, constituting a ship's windlass, which drum is hung at each end in parallel uprights B, so as to be free to turn.

C, a ratchet-toothed surface formed around the windlass at its centre, for receiving a pawl to hold the windlass from turning when desired.

D, the holding-pawl for windlass.

This pawl is constructed, as will be hereinafter explained, and is hung by a hinge or pivot-joint, E, to a post, F, above the windlass-drum A, extending therefrom over the windlass into position to interlock with its ratchet-teeth.

This pawl D is constructed of a blank-bar or plate, G, provided at one end with tubular eyes H, extending partially along upon its sides.

J, rods passing through each of the eyes H, in parallel planes.

These rods J play loosely through the eyes H, and are retained from escaping, at one end by pins a, and at their other, K, by being bent at right angles, meeting at or near the centre line of pawl. (See fig. 3.)

L², a cross-bar applied to rods J, and connecting the two together near their ends K, where it is secured from moving by suitable nuts d, and pins e, upon each side, as shown in fig. 3.

M, spiral springs, one around each rod J, between cross-bar L², and tubular eyes H.

A pawl constructed and hung to post, with the rods J toward the windlass, when dropped into the ratchet-teeth C, comes to a bearing in such teeth by the bent ends to said rods, (see fig. 2 more particularly,) and the pawl receives any strain or force exerted on the windlass from a sudden stoppage thereof in letting go anchor, from the riding or surging of a ship at anchor, and in dragging anchor, yielding or giving thereto, through a compression of its springs, which, when such straining or forcing subsides, throw the contact-end of pawl with windlass back to its original or normal contact-position.

By a yielding pawl, it is obvious the liability of its breakage, and also the windlass, is greatly, if not entirely prevented, while, at the same time, the windlass, under ordinary occasions, is securely held.

By pivoting or hinging the pawl to the post F, it can the more perfectly adjust itself to the ratchet-teeth, as the windlass is turned in consequence of strain thereon.

In lieu of constructing the contact-end of pawl with the windlass-ratchet in the peculiar manner described, it may be provided with a swivel or swinging catch-piece for the teeth, and also made in other respects varied in its construction and arrangement of parts; and furthermore, it may be fastened firmly to the post, in lieu of being hinged thereto, but it is preferable to hinge it.

In lieu of spiral, India-rubber or other forms of springs may be employed.

For indicating the amount of strain or force carried by the pawl D, one part G of it, along one or both of its edges O, is graduated, and their several graduations properly marked, so that by them, according to the distance which the rods are forced through the eyes H, along the said graduated edge O, the amount of force acting to compress the springs of the ratchet, will be indicated from time to time.

In lieu of graduating the edges O, the rods J may be graduated, the indication of pressure on the pawl being secured in either case.

Having thus described my invention, What I claim, and desire to secure by Letters Patent, is—

The pawl of ships' windlasses, constructed to yield or give to the movement of the windlass, for sudden strains thereon, and the above provided with graduations, substantially as described, for the purpose specified.

The above specification of my improvement in ships' windlass, signed by me, this 11th day of November, A. D. 1869.

E. B. RICH.
